UNITED STATES PATENT OFFICE.

JOHN W. ROCHFORD, OF WELLESLEY, MASSACHUSETTS.

MITER-BOX.

SPECIFICATION forming part of Letters Patent No. 367,849, dated August 9, 1887.

Application filed December 6, 1886. Serial No. 220,779. (No model.)

To all whom it may concern:

Be it known that I, JOHN W. ROCHFORD, a citizen of the United States, residing at Wellesley, in the county of Norfolk and Commonwealth of Massachusetts, have invented certain new and useful Improvements in Miter-Boxes, of which the following is a true and complete specification, reference being had to the accompanying drawings, and to the figures and letters marked thereon, forming a part of the said specification.

My invention relates to miter-boxes adapted for use with an ordinary crosscut-saw, and in which the miter-angle is adjustable at the will of the operator; and it consists of the devices and combinations herein described and shown.

Referring to the drawings, Figure 1 is an elevation of one of the slotted saw-guides. Fig. 2 is a perspective view of the sliding block and spindle to which it is attached. Fig. 3 is a view of the block and spindle which support the stationary slotted saw-guide. Fig. 4 is a vertical section on one of the saw-guides passing through its slot. Fig. 5 is a view of the miter-box complete. Fig. 6 is a vertical section of a saw-guide similar to that in Fig. 4, showing a modification in the manner of fastening the saw-guide to the guide-bars.

A is the base of the miter-box, into which are laid three strips of hard wood, a, a', and a'', radiating from the center of the rear stationary saw-guide, B, and inclining forty-five degrees, ninety degrees, and one hundred and thirty-five degrees, respectively, to the line of the back of the box C.

B, B', B'', and B''' are the upright slotted saw-guides, to be described hereinafter. The saw-guides B and B'' are stationary, and the line connecting their centers is perpendicular to the line of the back of C of the miter-box. To the front of the base A are attached the guide-bars D and D', which are separated from each other at each end by the blocks D'' D''. Each of the upright saw-guides consists of an iron frame, b, to which is attached the wooden guide-bars b' and b'' by the screws b¹⁰ b¹⁰ b¹⁰ b¹⁰. These screws move in slots b⁹ b⁹ b⁹ b⁹ in the frame b, and by loosening them the blocks b' and b'' may be made to approach or recede from each other, thus regulating the width of the slot which receives and guides the saw.

The frame b sets upon the block b⁴, which is provided with an upright grooved spindle, b⁶, which fits into a corresponding hollow in the base of the frame b of the saw-guide, the saw-guide being free to revolve upon the spindle b⁶ as an axis. The saw-guide is provided with a clamping-screw, b³, the end of which fits into the groove b¹¹ of the spindle b⁶ and prevents the saw-guide from being lifted from its place on the block b⁴. By tightening the clamping-screw b³ the saw-guide may be prevented from revolving on the spindle b⁶ as an axis. The block b⁴ has a tongue, b⁵, which fits into the space between the bars D and D', and a clamping-screw, b⁷, by which it may be clamped in any position upon the bars D and D'.

In Fig. 3 is shown the stationary block b⁸, which supports the saw-guide B, and is screwed to the back of the base A.

In Fig. 6 is shown a modification of my device for attaching the saw-guides to the guide-bars D and D'.

I provide the frame b with a spindle, b¹², which fits between the bars D and D', and is screw-threaded at its lower end to engage with a clamping-nut, b¹³. Between the clamping-nut and the bottom of the bars D and D', I place a washer, b¹⁴.

By loosening the clamping-nut b¹³ the saw-guide may be made to slide along the bars D and D' or turn on the spindle b¹² as an axis.

The miter-box is operated as follows: The strip whose end is to be mitered is laid upon the base A and firmly held against the back C. If it is desired to cut the strip off squarely, the stationary slotted saw-guides B and B'' are revolved on the spindles b⁶ b⁶, respectively, so that their slots lie in the same plane, and are fastened in that position by tightening the clamping-screws b³ b³. The saw is then inserted into the guiding-slots of the saw-guides B and B'' and the piece sawed off. If the piece is to be mitered, one of the saw-guides B or B''' is moved along the guide-bars D and D' until the angle between its center and the center of the saw-guide B and the line of the back C is equal to the desired miter-angle, and fastened in that position by means of a clamping-screw, b⁷. The saw-guides B and B' or B''' are then turned on their spindles b⁶ b⁶, respectively, so that their guiding-slots lie in the

same plane, and are fastened as before. The saw is then inserted in the slots and the piece sawed off.

By the use of the device shown in Fig. 6 5 the saw-guide B' or B² may be secured in any position on the guide-bars D and D' and its slot placed and held at the proper angle in one and the same operation by the clamping-nut b³.

What I claim is—

10 1. A miter-box having a vertical revolving saw-guide consisting of an upright slotted post having in its base a socket and a base-block provided with an upright spindle, in combination with horizontal stationary guide-bars, 15 whereby the saw-guide is placed at any angle at any point on said guide-bars, substantially as described.

2. A miter-box consisting of the base A, provided with two vertical saw-guides, B B², 20 horizontal guide-bars D D', and two sliding

vertical revolving saw-guides, B' B², all arranged and operated substantially as described.

3. A revolving vertical saw-guide having in its base a socket and a clamping-screw, in combination with a block which is provided with an upright grooved spindle, substantially as described. 25

4. A miter-box provided with horizontal guide-bars D D', a block, b¹, provided with a tongue, b⁵, a clamping-screw, b⁷, and an upright grooved spindle, b⁶, in combination with a revolving vertical saw-guide provided with a clamping-screw, b⁸, substantially as described. 30

In witness whereof I have hereunto set my hand. 35

JOHN W. ROCIFORD.
